UNITED STATES PATENT OFFICE

152,438

DESIGN FOR A SPOON OR ARTICLE OF SIMILAR NATURE

Fred J. Skrastin, Jr., Butte, Mont.

Application January 30, 1948, Serial No. 144,182

Term of patent 7 years

(Cl. D44—29)

To all whom it may concern:

Be it known that I, Fred J. Skrastin, Jr., a citizen of the United States, residing at Butte, in the county of Silver Bow and State of Montana, have invented a new, original, and ornamental Design for a Spoon or Article of Similar Nature, of which the following is a specification, reference being had to the accompanying drawings, forming a part thereof.

The essential features of my design for a spoon reside in the specific configuration of the handle portion shown in full lines.

I claim:

The ornamental design for a spoon or article of similar nature, substantially as shown and described.

FRED J. SKRASTIN, JR.
